UNITED STATES PATENT OFFICE

WILLIAM F. KRENZKE, OF RACINE, WISCONSIN, ASSIGNOR TO WALKER MANUFACTURING COMPANY, OF RACINE, WISCONSIN, A CORPORATION OF WISCONSIN

LIFTING JACK

Application filed August 3, 1930. Serial No. 297,839.

This invention relates to new and useful improvements in lifting jacks, and more particularly to a screw jack of the double extension type, designed to have a long lift in proportion to the size and height of the jack when in lowered or collapsed position.

The jack is of that type employing a plurality of telescopically engaged lifting and guide members, certain of which have screw threaded driving connections with one another, and others being keyed together to permit vertical sliding movement without permitting relative rotation.

The general object of this invention is to provide a jack of this type, as disclosed in detail hereinafter, which is capable of a maximum elevation in proportion to the initial height of the jack and the number of telescoping members used.

Another object is to provide a cupped driving gear mounted in the lower end of the supporting standard, so that the power may be most effectively applied, while at the same time permitting a maximum lowering of the lifting members.

Another object is to provide an improved form of sheet metal guide-sleeve.

Another object is to provide means for causing the guide sleeve to be elevated with the upper lifting member until the guide sleeve has reached its maximum elevation.

Another object is to provide a jack of this type which is simple and economical to manufacture, and easily assembled.

Other objects and advantages of this invention will be more apparent from the following detailed description of one approved form of the mechanism.

In the accompanying drawings:

Fig. 1 is a perspective elevation of the completely extended jack.

Fig. 2 is a central vertical section through the jack, when extended, as shown in Fig. 1.

Fig. 3 is a similar central vertical section, showing the jack completely lowered.

Fig. 4 is a horizontal section, taken substantially on the line 4-4 of Fig. 3.

Fig. 5 is a detail perspective, on a larger scale, of the driving gear and tubular driving member carried thereby.

The supporting standard comprises a suitable base plate 1, and a hollow standard 2 which may be made of malleable iron, or of pressed steel parts suitably assembled. Standard 2 comprises an enlarged lower end portion 3 having an out-turned end flange 4, by means of which the standard is secured to base plate 1. The smaller upper end portion 5 of standard 2 is in the form of a cylindrical guide portion, having a vertical projection 6 at one side which houses the vertical guide groove 7. An outwardly extending and upwardly inclined tubular bearing 8 formed in one side wall of standard 2 intermediate its upper and lower ends, receives the journal 9 of the driving pinion 10. A hand wheel or disc 11, for conveniently rotating the driving pinion, is mounted on the outer end of journal 9, and a non-circular socket 12 in journal 9 is adapted to receive the correspondingly shaped end of a driving handle, whereby the jack may be operated from a distance when lifting or lowering the load.

The improved driving gear (shown in perspective in Fig. 5), comprises a base portion or disc 13, from which arise the vertical substantially cylindrical side walls 14. An inwardly extending flange 15 at the upper end of cylindrical portion 14 is formed with an annular series of gear teeth 16 adapted to mesh with the driving pinion 10. The lower outer edge portion of this gear member is inset or curved inwardly, as indicated at 17, to house the members of an annular roller bearing 18. This bearing comprises a lower race-way 19 carried by base plate 1 and centered by engagement with the lower end of standard 3, and an upper race-way 20 centered in the annular depression 17 in the gear member. In this manner the gear member is rotatably supported from the base 1, and centered within standard 2, with the base portion 13 of the gear positioned as closely as possible to the base plate 1 and the cylindrical outer walls 14 of the gear member closely adjacent the side walls of standard 2, so that the lifting members, hereinafter described, may be telescoped within the gear member with their lower edges brought into close proximity to the base 13 of the gear, and as

closely as possible to base plate 1, whereby a maximum lowering of the lifting members is made possible.

5 A hollow tubular driving member 21 is mounted at its lower end in base 13 of the driving gear, the central portion of the gear preferably being cut away, as indicated at 22, so that the opening in tubular member 21 extends clear down to base plate 1, thus 10 permitting a maximum lowering of the lifting screw 23, hereinafter described. The upper end portion of tubular driving member 21 is interiorly threaded, as indicated at 24, to receive the screw 23 which is threaded exteriorly substantially from end to end there- 15 of. A stop 25 secured in the lower end portion of screw 23, is adapted to engage the lower end of threads 24 to limit the upward movement of the screw.

20 An enlarged head 26 exteriorly threaded at 27, is keyed on the upper end of screw 23, as indicated at 28. An upper tubular lifting member 29 is interiorly threaded at 30 to receive the head 26. The upper end of lifting member 29 is provided with a suitable load-engaging head or plate 31.

25 A guide sleeve 32 is preferably formed of sheet material bent to form a hollow cylindrical portion which will fit telescopically 30 within the upper cylindrical end 5 of standard 2, and a vertical hollow rib 33 adapted to slide within the groove 7 in the standard. This rib may be conveniently formed by bending outwardly the walls of the sleeve, as indicated at 34 and 35, and then bending toward one another and overlapping the ends 36 and 37 of the sheet from which the tube is formed. These overlapping wall portions may be united by welding, or by rivets, as indicated at 38 and 39. As here shown, the lower rivet 38 serves as a stop member, which engages the inset portion 40 at the upper end of groove 7 of the standard for limiting the upward movement of sleeve 32. It will 40 be apparent that the engagement of rib 33 within the groove 7 in the standard will prevent relative rotation between the guide sleeve 32 and the standard, and an outwardly extending projection 41 on the lower end of the upper lifting member 29 slides in the groove 42 formed in hollow rib 33 so as to prevent relative rotation between the sleeve 32 and lifting member 29. Since the supporting standard is held from rotation by its 45 engagement with the ground or other supporting surface, it will be apparent that the upper lifting member 29, which supports the load, is never permitted to rotate.

50 A spring latch 43 is mounted in the upper portion of groove 42 in sleeve 32, as by means of the rivet 39. The inturned finger 44 at the upper end of spring latch 43 is adapted to detachably engage in a notch 45 formed 55 adjacent the upper end of lifting member 29.

The latch is shown in engaged or latching position in Fig. 3.

When the jack is completely lowered, as shown in Fig. 3, all of the lifting and guide members will be completely housed within the standard 2. It will be noted that the screw 23 can be made of a maximum length so as to extend completely down to the base plate 1. The guide sleeve 32 and upper lifting member 29 telescope down over the tubular driving member 21, and within the cup shaped gear member so as to extend at their lower ends closely adjacent the base 13 of the gear.

When the driving pinion is rotated in the proper direction for elevating the jack, the lifting screw 23 which is held from rotation, due to its engagement with upper lifting member 29 (there usually being greater frictional resistance between the threaded head

26 and the internally threaded lifting member 29 than there is between the screw 23 and the nut 24) will be elevated through the nut 24 carrying upwardly with it the upper lifting member 29 and any load that may be supported thereby. The guide sleeve 32 will also be carried up along with screw 23 and lifting member 29, since latch 43 is now in engagement with the notch 45 in the lifting member. When screw 23 reaches the upper limit 50 of its travel, as shown in Fig. 2, the stop 25 having engaged the lower end of threads 24, it will be forced to rotate with the tubular driving member 21, thus rotating head 26 within the upper lifting member 29 and causing that member to be raised out of guide sleeve 32. When further upward movement of guide sleeve 32 is prevented by the stop 38 engaging the stop 40 on the standard, the spring latch 43 will snap out of the notch 45 105 and permit the lifting member 29 to move upward to the extreme position shown in Fig. 2, where further elevation of the jack members is prevented by the engagement of projection 41 with the lower end of latch member 43. During this latter movement of lifting member 29, the finger 44 on spring latch 43 will simply bear yieldingly against the outer cylindrical surface of lifting member 29. The jack is again lowered by a reverse rotation of the driving pinion, and when the members have been completely telescoped within the standard, the spring latch 43 will again snap into the notch 45 in lifting member 29, as shown in Fig. 3.

110 By providing means for causing the guide sleeve 32 to be elevated during the first half of the load-lifting operation, the lifting members are additionally stiffened during this phase of the movement, and the sleeve 32 is relieved of some of the maximum twisting strains to which it would otherwise be subjected.

115 F claim:

120 1. In a lifting jack, a supporting member

- comprising a base plate and a hollow upright standard carried thereby, a driving pinion mounted in one wall of the standard intermediate the ends thereof, a cup shaped driving gear consisting of a horizontal base, a substantially cylindrical portion arising therefrom adjacent the inner side walls of the standard, and an annular series of gear teeth formed at the upper end of the cylindrical portion and adapted to mesh with the driving pinion, an annular bearing inset in the outer edge portion of the driving gear for supporting same from the base plate with the gear base positioned closely adjacent the base plate, an upright hollow cylindrical driving member mounted centrally in the gear base and secured thereto, the upper end portion of this member being interiorly threaded, a lifting screw meshing with these threads and adapted to telescope within the driving member, an exteriorly threaded head on the upper end of the screw, a hollow interiorly threaded lifting member in which the head meshes, a hollow guide sleeve formed with an outwardly projecting hollow vertical rib at one side thereof, the upper portion of the standard being formed to slidably receive the sleeve and rib, the lower end of the lifting member having a projection thereon adapted to slide vertically in the hollow rib, stop members on the standard and sleeve, and a spring latch mounted in the upper portion of the hollow rib of the sleeve and detachably engaging the lifting member so that the sleeve will be carried up with the lifting member until further upward movement thereof is prevented by the engagement of the stop members.
2. In a lifting jack, a supporting member comprising a base plate and a hollow upright standard carried thereby, a driving pinion mounted in one wall of the standard, a horizontally disposed driving gear meshing with the pinion, a bearing for supporting the gear from the base plate, a tubular vertically extending driving member mounted centrally on the driving gear, the tubular member being interiorly threaded at its upper end, a lifting screw threaded in the tubular member, an exteriorly threaded head mounted at the top of the lifting screw, a hollow interiorly threaded lifting member in which the head meshes, a hollow guide sleeve telescopically engaging the standard and the hollow lifting member, there being slidably interengaged portions on the sleeve, standard and lifting member to prevent relative rotation of these members, a stop for limiting the upward movement of the sleeve, and a spring latch detachably connecting the sleeve and lifting member so that the sleeve and lifting member will be elevated as a unit until the stop prevents further upward movement of the sleeve.
3. In a lifting jack, a supporting member comprising a base plate and a hollow upright standard carried thereby, a driving pinion mounted in one wall of the standard, a horizontally disposed driving gear meshing with the pinion, a bearing for supporting the gear from the base plate, a tubular vertically extending driving member mounted centrally on the driving gear, the tubular member being interiorly threaded at its upper end, a lifting screw threaded in the tubular member, an exteriorly threaded head mounted at the top of the lifting screw, a hollow interiorly threaded lifting member in which the head meshes, a hollow guide sleeve telescopically engaging the standard and the hollow lifting member, there being slidably interengaged portions on the sleeve, standard and lifting member to prevent relative rotation of these members, stop members on the sleeve and standard for limiting upward movement of the sleeve, and a spring latch mounted in the upper end of the sleeve and detachably engaging the lifting member so that the sleeve will be carried up with the lifting member until further upward movement thereof is prevented by the stop members.
4. In a lifting jack, a hollow standard formed at its upper end with a cylindrical portion with a vertical guide groove projecting outwardly from one side thereof, a hollow cylindrical guide sleeve formed with a hollow longitudinal rib projecting outwardly therefrom and slidably received in the groove, a cylindrical lifting member telescopically received in the sleeve and having a projection on its lower end portion slidable in the hollow rib, and means mounted in the standard and engaging the lifting member for raising and lowering the same.
5. In a lifting jack, a hollow standard formed at its upper end with a cylindrical portion with a vertical guide groove projecting outwardly from one side thereof, a hollow cylindrical guide sleeve formed with a hollow longitudinal rib projecting outwardly therefrom and slidably received in the groove, a cylindrical lifting member telescopically received in the sleeve and having a projection on its lower end portion slidable in the hollow rib, stop members on the standard and sleeve, and a spring latch mounted in the hollow rib and detachably engaging the lifting member so that the sleeve will be carried up with the lifting member until further upward movement thereof is prevented by the engagement of the stop members, and means mounted in the standard and engaging the lifting member for raising and lowering the same.
6. In a lifting jack, a hollow standard formed at its upper end with a cylindrical portion with a vertical guide groove projecting outwardly from one side thereof, a hollow guide sleeve formed of sheet metal bent to form a cylindrical portion and an out-

wardly extending hollow vertical rib, the edges of the metal sheet being overlapped to form the outer wall of the rib, the rib being slidably received in the groove of the standard, a cylindrical lifting member telescopically received in the sleeve and having a projection on its lower end portion slideable in the hollow rib, and means mounted in the standard and engaging the lifting member to raise and lower the same.
